UNITED STATES PATENT OFFICE

MARK W. PETERS, OF GLEN RIDGE, NEW JERSEY, ASSIGNOR TO EAGLE PENCIL COMPANY, OF NEW YORK, N. Y., A CORPORATION OF DELAWARE

DESIGN FOR A PENCIL

Application filed July 30, 1931. Serial No. 40,733. Term of patent 7 years.

To all whom it may concern:

Be it known that I, MARK W. PETERS, a citizen of the United States, residing at Glen Ridge, in the county of Essex and State of New Jersey, have invented a new, original, and ornamental Design for a Pencil, of which the following is a specification, reference being had to the accompanying drawings, forming part thereof, in which

Fig. 1 is an end view of the top of the pencil; and

Fig. 2 is an elevation of the pencil.

I claim:

The ornamental design for a pencil, substantially as shown.

MARK W. PETERS.
